UNITED STATES PATENT OFFICE.

WILLIAM P. THOMSON, OF FOREST HILLS, LONG ISLAND, NEW YORK, ASSIGNOR TO
THE RAIL JOINT COMPANY, OF NEW YORK, N. Y., A CORPORATION OF NEW YORK.

SAFETY-INDICATOR FOR RAILWAY-TRACKS.

1,386,290.

Specification of Letters Patent. Patented Aug. 2, 1921.

Application filed March 15, 1921. Serial No. 452,587.

To all whom it may concern:

Be it known that I, WILLIAM P. THOMSON, a citizen of the United States, residing at Forest Hills, Long Island, in the county of Queens and State of New York, have invented certain new and useful Improvements in Safety-Indicators for Railway-Tracks, of which the following is a specification.

10 This invention relates to the subject of track maintenance, and particularly refers to a novel auxiliary device employed in connection with the rail ends to provide safer and more economical track conditions, 15 said device primarily operating to indicate serious track conditions arising from abnormal stresses and also functioning as an adjunct to protect the rails from damage.

20 The important object of the invention as a safety indicator for railway track to provide a means for respectively indicating safe and unsafe rail end separation will better be understood by reference to certain track conditions to which the invention is especially addressed.

25 Referring particularly to those conditions, it should be stated at the outset that more damage seems to result from one rail running tight up against an adjacent rail than from one rail running away from an adjacent rail; in other words, tightly abutted rail ends are productive of greater damage than is at all likely to result from any condition arising from normal or even an excessive amount of free space between adjacent rail ends.

30 An excessive opening between rails is so obviously wrong that track men, even if accustomed to exercise only reasonable care, 40 are usually impressed with the necessity for correcting such a condition at the first opportunity.

On the other hand, when adjacent rails have no space between their ends, it is not 45 customary in present practice to question what may be the extent of the force which one of the rails may be exerting upon the other rail; it may be negligible or it may be great enough to maintain such stress in 50 the track that the disturbance caused by a moving train, or the exceeding of the resistance to displacement of any certain degree of curved track, may be sufficient to

break a rail or throw the whole track out of its true alinement and thus instantly create 55 a perilous condition as suggested by the diagram of Fig. 6. This is an extreme but not uncommon occurrence.

There exist, however, intermediate of these conditions of negligible and perilous 60 stresses, certain well defined conditions which are productive of exceedingly troublesome disturbances of normal operative relations of the component parts of a section of track. These other conditions are 65 relatively of such secondary importance that no detailed explanation is deemed necessary for those familiar with such matters. What may be termed the primary conditions, however, are productive of such damage to 70 the rails themselves as to constitute an enormous factor of expense in the matter of abnormally rapid deterioration of the rail and the most damaging of these conditions, at least, should be noted, viz:—

75 First—Rails over which the traffic is in one direction may rest so firmly and continuously in contact with each other that the running surface of the end of the leaving rail will become elevated to a sufficient 80 extent above the surface of the receiving rail that the passing wheels will regularly jump from the higher elevation to the lower. The result, which is very commonly noticeable in track, is that the receiving rail is 85 hammered to a lower and lower level while the surface of the leaving rail is being rolled to a higher and higher level, with such certainty that in time the receiving rail assumes a contour which is noticeably broader 90 and flatter than that of the leaving rail, and, if the action is permitted to persist, the receiving rail becomes actually cupped. Such rail is ruined and the damaged ends are frequently sawed off to render the rest of the 95 rail usable.

Second—Track conditions may be such that, with the traffic in one direction, the rails will abut tightly against each other and will have a space between them in intermittent fashion, due to expansion and contraction under the influence of atmospheric conditions. In most of such instances, the abutting relationship predominates to such an extent that the running 100 surface of a hard leaving rail becomes ele- 105

vated (but not to the same extent as in the first illustration above) and, when contraction of the rails produces an opening, this elevated surface is rolled very quickly to a greater or less extent into the interspace. Just as soon, however, as the expansion, or other action, restores the abutting condition, the metal which had flowed into the interspace is crowded back against the upper corner of the leaving rail with such force that it usually becomes detached from the rail and carries with it a piece of the top surface of the leaving rail, thus producing a result commonly known as "chipping" of the rail end. Another variety of "chipping" is caused under similar conditions when the rail is comparatively soft. Then the rolling action of the wheels on tightly abutting rails causes metal to flow from the running surface of the leaving rail over upon the top of the receiving rail to quite an extent, if the rail joint is tight, but just as soon as any looseness of the rail joint occurs the overlapping metal is torn away and usually carries with it a larger chip from the surface of the leaving rail than under the circumstances described where the rail is harder.

Third—Rail breakage is certainly more liable to occur if tightly abutting rail ends permit abnormal stress to occur in a rail, particularly in a straight rail. Considering, for example, a straight rail which is being subjected to abnormal stress as it lies in repose in the track, the lines of force then are all parallel to the longitudinal axis of the rail, but the moment a wheel load causes deflection of the rail all of this abnormal force, except that through the center of gravity of the rail, is converted into abnormal tension or compression stress, over and above the normal stresses due to the rail deflection; and it needs no further demonstration to prove to those familiar with such conditions how great may be the latent power for damage which may reside in an abnormally stressed rail, particularly where it is recalled that the factor of temperature alone may account for an accumulation of unit stress of 2240 pounds per square inch for every increase of temperature of 12 degrees Fahrenheit.

It will, therefore, be seen that a broad and comprehensive aspect of the invention is in the purpose to provide a safety device for railway track which takes into consideration the varying properties of rail steel and the extremely variable conditions of track locations and the intensity and severity of traffic, whereby the device will function effectively to establish a minimum spacing of rail ends, regardless of temperature spacing, beyond which track and traffic and weather conditions may not encroach until they produce a force which becomes so abnormal that

the failure of the device, which may be termed a gage, having a safe crushing limit, will constitute an indicator to warn against the existence of an abnormal force, and its nature may be determined and corrected. 70

Also as pointed out, one phase of the invention is to provide a reliable and safe means for limiting stresses to alleviate or prevent the chipping or battering of the running surfaces at the ends of adjacent 75 rails.

Therefore, it will now be understood that a distinctive purpose of the invention may be to provide what may be termed a safety gage adapted to be located between the rail ends and having such a "yieldpoint" to compressive force that its resistance is superior to normal compressive forces, within safe limits, and which is inferior to abnormal compressive forces. Thus, one of the primary purposes of the invention is to provide a gage of the character referred to which will be crushed to a negligible thickness within a safe limit of time before any danger would arise due to springing or "sun-kinking" 90 of the rails. Such characteristic action would preclude absolutely tight laying of rails except as the result of authoritative instruction to omit the use of the safety gage. 95

An incidental but practical and important object of the invention is to provide the gage with means adapting it for use as a rail end spacing gage in accordance with standard practices for atmospheric or other conditions, that is, permitting the track men to use the device to obtain the prescribed spacing of the rail ends when the rails are laid. After such use, the device is intended to be left between the rail ends to perform the special safety functions above pointed out. 105

With these and other objects in view, which will be apparent to those skilled in this art, the invention consists in the novel construction and relation of elements herein-after more particularly pointed out, illustrated and claimed. 110

Though susceptible of embodiment in a wide range of structural forms, certain preferred and practical embodiments are shown in the accompanying drawings, in which— 115

Figure 1 is an elevation of adjacent rail ends showing the novel safety gage placed between the ends thereof in operative relation thereto. 120

Fig. 2 is a vertical sectional view through the joint shown in Fig. 1 exposing the safety gage and one rail end in elevation and showing by dotted lines splice bars which act to sustain the gage in place. 125

Fig. 3 is a top view of the joint shown in Fig. 1 showing the cross section of the gage waved.

Fig. 4 is a detail view of a modification of the shank member of the gage. 130

Fig. 5 is a graphic diagram, magnified, 5 illustrative of the development occurring from a normal spacing of the rail ends, with the safety gage in place, to the stage where abnormal compressive force operates to reduce the gage to a negligible thickness indicating possible unsafe track.

Fig. 6 is a diagram of a section of track showing curves of different degree ($s-t$, 10 $u-v$) and their associated tangents ($r-s$, $t-u$ and $v-w$), indicating by dotted lines the throwing of the track out of its true alinement, particularly at the curves, due to disturbances caused by a moving train augmented by abnormal stresses in tightly abutting rails.

Fig. 7 is a detail view similar to Fig. 2 illustrating that form of the invention wherein the head member of the gage is provided with a series of graduated gaging elements for setting the rail ends to prescribed spacing when laying the rails.

Fig. 8 is a diagrammatic view, illustrating by a series of diagrams, the use of the gage 25 for setting the rail to a prescribed spacing.

Like reference characters designate corresponding parts throughout the several figures of the drawings.

In carrying forward the invention, the 30 structural form thereof may be greatly varied, and different materials employed, provided that the essential characteristics and functions of the device are preserved. For example, however, there are shown in 35 the drawings certain forms of construction which may be utilized to advantage in the fulfillment of the objects of the invention.

Referring first to that form shown in Figs. 1, 2 and 3 of the drawings, it will be observed 40 that the same comprises a gage body designated generally by the reference letter A having approximately the cross sectional form of a rail head and rail web and made, if desired, of steel wire or equivalent material having the capacity to offer the variable resistance to crushing force as contemplated by the present invention.

The gage body, as shown in the figures referred to, includes a shank member 1 consisting of the end portions of the wire, being arranged in substantial parallelism, forming a convenient handle as hereinafter explained and lying between the ends of the webs of the adjacent rails. The top portion 55 of the gage body constitutes a head member having the outwardly and upwardly inclining side bearing arms 2 which have their bearing support on the heads of the splice bars S, and connecting the said side bearing arms 2 is the crown or mid-section 3 of the device, which section 3 lies between adjacent rail heads and extends transversely across the space between them.

As above pointed out, it is the purpose of 60 the invention to provide a gage body hav-

ing a "yield point" which is superior to normal compressive forces and which is inferior to abnormal compressive forces, so that at a predetermined limit of resistance, the gage body will break down, gradually or 70 abruptly according to specific characteristics of the style of gage preferred, to operate an indicator of an unsafe track condition. Therefore, different gages having different "yield points" may be employed in carrying 75 out the invention. In other words, different gages may be given different limits to crushing which will be properly predetermined. However, the action of the improved safety gage may be explained in connection with that example shown in the drawings, wherein the body of the gage preferably has a malleable characteristic and its functioning is shown by the graphic diagram of Fig. 5 which is a magnified illustration of the range of rail separation from $\frac{3}{8}$ of an inch to $\frac{1}{4}$ of an inch. The first view of this diagram shows a normal condition and the succeeding views illustrate the development occurring from an increase in the 80 compressive forces exerted against the interposed gage, reaching to a point where these forces become abnormal, and the final view showing the gage body broken down or crushed to a negligible thickness, indicating 85 unsafe track conditions.

From the foregoing, it will be seen that a preferable construction is to have the gage made of a malleable body, that is malleable in the sense of being susceptible of malleation under abnormal conditions by the crushing force of the rails due to expansion, track or traffic conditions, it having been already pointed out that it is intended that the gage shall be crushed to a negligible thickness, by 90 malleation before there is any danger of springing or "sun-kinking" of the rails. Also in connection with this malleable characteristic of the gage body, a form of construction may be employed which will permit an exact limit of resistance to crushing of the gage to be varied to quite an extent 95 to meet atmospheric or local conditions without affecting materially the primary purpose of this invention.

Therefore, it is proposed, preferably, to provide the gage body with means giving to the gage a graded resistance or a plurality of "yield points," the highest of which is the determining factor within the intent of the 100 invention. For instance, that phase of the invention may be realized in providing the crown or mid-section 3 of the gage body with laterally displaced contact points or bends 4 which may be conveniently produced 105 by waving or crimping said crown or midsection 3. Or as may be involved in a form of the invention such as shown in Fig. 5, the body of the gage may have the feature of 110 variability or gradation of resistance in- 115 120 125 130

corporated therein by making its interior of more highly resistant material than its exterior, or by making it dependent merely upon the circular contour of the wire of which it may be composed, as will be apparent by reference to the diagram of Fig. 5. However in whatever way that feature may be incorporated in a gage body, the result is the same, namely that of providing the gage body with what may be termed normal resistance means having a "yield point" which is high enough to enable it to resist compression strains imposed by the adjacent rail ends under normal track conditions; and also providing the gage body with what may be termed maximum or ultimate resistance means, the yield point of which is not high enough to enable it to keep the rails from crushing the spacing gage under dangerously high stresses.

The carrying forward of the special objects noted may, as stated, be embodied in a variety of forms of construction and a modification that may be resorted to as to one of the details, is that shown in Fig. 4 of the drawings, which consists in twisting the shank member of the gage body, thus making the structure more compact, as well as affording a convenient handle when the crown of the gage is formed, as in Fig. 8, for use as a temperature shim on new rail laying.

An adaptation of the device for use as a temperature gage, for gaging the spacing of rails when laid, is shown in the special form of gage illustrated in Figs. 7 and 8 of the drawings. It will be seen from the illustration of these figures, that the function referred to may very effectually be performed by constructing the head member of the gage body with an unsymmetrical series of steps, producing a series of graduated gaging elements *a*, *b*, *c*, *d* and *e*. These gaging elements divide the head member of the body into a number of different depths providing means, when inserted between rail ends, of accurately determining a number of spaces or gaps which may be left between the rail ends when the rail is laid according to local atmospheric conditions. This use of the invention is graphically shown in the series of diagrammatic outlines of Fig. 8 of the drawings. After the gage has been used in this manner, it is then placed between the rail ends to perform the additional function as a safety gage in the manner hereinbefore fully described.

It should be pointed out, in connection with the use of the device as a temperature gage that where such a variety of spacing is not required as provided for by the device shown in Figs. 7 and 8 of the drawings, the crimping of the crown of the device as shown in Figs. 1, 2 and 3 or twisting of the

shank as suggested in Fig. 4 may be done to such a measured extent as to afford an accurate measure, to any predetermined extent, for use as a temperature gage for any single amount of spacing between the rail ends when the rail is being laid. In other words, the act of inserting such a gage would operate automatically to space the rails to one fixed distance when brought up against the gage.

Other modifications of the invention may be resorted to and various changes in the form, proportion and minor details of construction may be employed without departing from the spirit or sacrificing any of the advantages of the invention.

I claim:

1. A safety indicator for railway track having means for respectively indicating safe and unsafe longitudinal stresses in two rails which abut against said indicator.

2. A device of the class described consisting of a body adapted to be interposed between rail ends and having a yield point superior to normal compressive forces and inferior to abnormal compressive forces.

3. A device of the class described consisting of a body adapted to be interposed between adjacent rail ends and provided with normal resistance means having a yield point sufficiently high to resist normal compressive strains, and a maximum or ultimate resistance means having a yield point inferior to an abnormal crushing force.

4. A safety gaging means adapted to lie in an interspace between rail ends and having a yield point above which abnormal stresses will break down the gage and close up the gap.

5. A gage of the class described adapted to lie between adjacent rail ends and having a range of resistance to compressive forces up to a point beyond which said forces are to be regarded as dangerous.

6. A gage of the class described adapted to lie between adjacent rail ends and having a range of safe resistance to compressive forces, within which a minimum gap between rail ends cannot be diminished.

7. A gaging medium adapted to be interposed between adjacent rail ends and consisting of a gage body having component parts which are of a rounded sectional conformation.

8. A gaging medium adapted to be interposed between adjacent rail ends and consisting of a gage body having component parts all of which have the same ultimate and safe yield point to compression but some of which parts have various degrees of lower resistance to compression.

9. A device of the class described consisting of a body adapted to be interposed between rail ends and having a graded resistance to compressive forces.

10. A device of the class described consisting of a metallic body adapted to be interposed between rail ends and inherently having a plurality of yield points. 20
- 5 11. A rail spacing device having a plurality of yield points so graded as to afford safe resistance to compression up to an ultimate yield point at which the resistance breaks down before track stresses have 10 reached their danger point.
12. A gage of the class described having a metallic body adapted to be placed between rail ends and susceptible of cumulative resistance to malleation up to a point where it 15 indicates a dangerous intensity of longitudinal stresses in the rails.
13. A metallic gage of the class described comprising a malleable gage body adapted
- to be placed between rail ends and inherently having a graded resistance. 20
14. A gage of the class described consisting of a gage body formed of wire. 25
15. A gage of the class described consisting of a gage body formed of wire and including a shank member and a head member both of which have the same ultimate yield point to compression but one of which may also have a lesser yield point than the ultimate. 30
- In testimony whereof I hereunto affix my signature in the presence of two witnesses.
